UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

STAY-BOLT STRUCTURE.

1,291,787.

Specification of Letters Patent.

Patented Jan. 21, 1919.

Application filed April 26, 1918. Serial No. 230,906.

To all whom it may concern:

Be it known that I, ETHAN I. DODDS, a citizen of the United States, and a resident of Pittsburgh, in the county of Allegheny and State of Pennsylvania, have invented certain new and useful Improvements in Stay-Bolt Structures; and I do hereby declare the following to be a full, clear, and exact description of the invention, such as will enable others skilled in the art to which it appertains to make and use the same.

This invention relates to improvements in staybolt structures and more particularly to the closure construction for the bearing sleeve,—the object of the invention being to provide simple and efficient means whereby a removable cap or closure may be normally held tightly to its seat and at the same time permit of the quick removal of said cap to enable the bolt to be tested and as quickly replaced and secured.

With this and other objects in view, the invention consists in certain novel features of construction and combinations of parts as hereinafter set forth and pointed out in the claims.

In the accompanying drawings; Figure 1 is a sectional view illustrating an embodiment of my invention; Fig. 2 is a plan view with the cap head removed, and Fig. 3 is a separate view of the locking member.

1 represents a bearing sleeve which may be externally threaded to screw through a suitable hole in a boiler sheet and having a curved interior face 2 which serves as a bearing for the curved or spherical head 3 of a stay bolt 4.

The body portion of the sleeve is made with an extension 5, the inner wall of which is offset somewhat from the bore of the body of the sleeve to form an annular seat 6 for a cap or closure 7,—the latter being made on its underside near its periphery with a slight annular enlargement 8 to facilitate accurate seating of said cap or closure.

The cap 7 is provided on its top with an enlargement 9 from which a shank 10 having a left hand screw-thread projects,—said shank having such diameter relatively to that of the top of the enlargement 9 as to leave an annular shoulder 11 surrounding the base of the shank. The outer end portion of the threaded shank 10 enters a threaded socket in a cap head 12 and is rigidly secured to the latter by means of a

pin or key 13. The cap head 12 may have a general hemispherical shape and is provided with a peripheral flange 14 which freely encircles the outer end portion of the bearing sleeve extension.

The bearing sleeve extension 5 is provided interiorly at or near its free outer end with flanges or shoulders 15 spaced apart in a manner to form notches 16. A securing member 17 is threaded on the shank 10 and when the parts are first assembled, this locking member may rest upon the shoulder 11 of the enlargement 9. The locking member is provided with lugs 18 which pass through the notches 16 when it is inserted into the sleeve extension 5, and when said locking member is turned, the lugs will become disposed behind the flanges or shoulders 15 in the bearing sleeve extension 5. The locking member is also provided with stop shoulders 19 to engage end portions of the flanges or shoulders 15 and thus limit the turning movement of said locking member.

When the parts shall have been assembled as above described, continued turning force applied to the cap head will cause the locking member to tend to move outwardly on the threaded shank and the cap or closure to be pressed tightly against its seat. Thus the cap or closure will be securely held in its normal position.

It is apparent that by a reversal of the operations above described, the cap or closure will be unlocked and may be quickly removed to give access to the head of the stay-bolt for testing the latter. It is equally apparent that the parts may be as quickly reassembled and the cap or closure secured in its normal position.

Having fully described my invention what I claim as new and desire to secure by Letters-Patent, is:—

1. In a staybolt structure, the combination with a bearing sleeve having a cap seat and having an extension provided with internal shoulders, of a cap to rest on said seat, a threaded shank rigid with said cap, a cap head secured to said shank and closing the outer end of the bearing sleeve extension, and a securing member threaded on said shank, said securing member having lugs to underlie the shoulders in the sleeve extension and also having stops to engage said last-mentioned shoulders.
2. In a staybolt structure, the combina- 110

tion with a bearing sleeve having a cap seat and a sleeve extension, said sleeve extension having internal shoulders at its outer end portion spaced apart to form notches between their ends, of a cap to enter said sleeve extension and rest on said cap seat, a threaded shank rigid with said cap, a cap head threaded on and rigidly secured to said shank, said cap head having a flange encircling the outer end portion of said sleeve extension, and a securing member threaded on said shank and having lugs to enter behind the shoulders in the sleeve extension and having stops to engage said shoulders.

3. In a staybolt structure, the combination with a bearing sleeve having a cap seat and a sleeve extension, the latter having internal shoulders spaced apart at its outer

end portion, of a cap to rest on said seat, an enlargement on said cap, a threaded shank projecting from said enlargement, the latter providing an annular shoulder around the base of said shank, a cap head secured to said shank, a securing member on said shank and disposed over said annular shoulder, said securing member having shoulders to underlie the shoulders in the sleeve extension and also having stops to engage said shoulders.

In testimony whereof, I have signed this specification in the presence of two subscribing witnesses.

ETHAN I. DODDS.
